UNITED STATES PATENT OFFICE.

ALEXANDRE LAMBLIN, OF PARIS, FRANCE.

RADIATOR FOR USE IN INTERNAL-COMBUSTION ENGINES.

1,317,200.

Specification of Letters Patent. Patented Sept. 30, 1919.

Application filed February 15, 1918. Serial No. 217,427.

To all whom it may concern:

Be it known that I, ALEXANDRE LAMBLIN, citizen of the Republic of France, residing at No. 7bis Rue Labrouste, Paris, France, have invented certain new and useful Improvements in or Relating to Radiators for Use in Internal-Combustion Engines, of which the following is a specification.

Radiators as at present applied to the 10 motors of dirigibles and aeroplanes present numerous disadvantages of which the principal ones may be summed up as follows:—

Whether they be of the so called honeycomb type or of the tubular type they take 15 up much space, are of considerable weight and offer substantial resistance to the flight of the airship.

Since the circulation of the water takes 20 place in a vertical direction by bundles which present in the direction of motion a vertical wall, the radiator not only offers a resistance to the forward movement and also gives rise at the rear, to the creation of a 25 vacuum or partial vacuum which further augments this resistance, but the movement of the liquid is impeded by its inertia; the liquid mass necessarily participating in the horizontal movement of the apparatus.

On the other hand the known type of radiators 30 cannot be repaired once they are placed on the apparatus, they are still less capable of repair when the airship is in motion.

In tubular radiators as in the "honeycomb" type radiators the air having to 35 traverse either tubular conduits of great depth or a bundle composed of several rows of tubes, becomes rapidly heated up therein, so that the cooling of the water becomes in- 40 sufficient at the rear of the radiator.

Finally the present type of radiators have 45 no practical device for filling them and maintaining them full of water.

The radiator which forms the subject matter 50 of my invention is exempt from all these disadvantages.

According to my invention the tubes of 55 the radiator which are preferably made of the new special form hereinafter described, are arranged at a suitable distance apart in, preferably, a single layer, uniformly distributed around a horizontal axis, that is to say around an axis parallel to the longitudinal axis of the airship. The tubes open to 60 this end, at their extremities, into a front

and a rear collector respectively, both of which are annular and arranged in planes at right angles to the horizontal axis of the layer of tubes. A system of circulating pipes in which is inserted the pump, connects the two collectors with each other. 60

As is shown in the particular constructional forms illustrated by way of example, the layer with the horizontal axis along which tubes of the radiator are distributed, will preferably be a surface of revolution of ovoid form (*i. e.* of streamline form) presenting a straight circular section reduced at the rear and its straight section greatest near the front at a suitable distance from 70 the mouths of the tubes in the front collector. The result is a maximum distance apart of the tubes near the front and a minimum distance apart near the rear.

The distribution of the tubes in a single 75 layer around a horizontal longitudinal axis or a practically horizontal axis suppresses or reduces to a minimum (in the thickness of the annular collectors) the vertical walls and consequently the resistance to advance 80 due to these walls. It also facilitates the circulation of the cooling water which is effected principally in the direction in which the apparatus advances.

Furthermore when the layer of tubes is 85 arranged around an ovoid surface as above defined, the rear vacuum or partial vacuum due to the circulation of the air is reduced to a minimum, and separate currents of cooling air circulating simultaneously inside 90 and outside the bundle the result is that the cooling effect becomes of maximum intensity, the tubes being subjected to the cooling action over their whole surface. The access of the air and its flow are by reason of 95 the greater distance apart of the front tubes also facilitated in that part where the water enters at the highest temperature.

The constructional forms illustrated also 100 present other important characteristics hereinafter referred to so that an apparatus is obtained not presenting any of the disadvantages enumerated above.

Figure 1 of the accompanying drawing shows in longitudinal sectional elevation a 105 radiator in accordance with my invention.

Fig. 2 is an end view the right hand half being in elevation and the left hand half a transverse section on the line 2—2 of Fig. 1.

Fig. 3 shows a modification, the lower half 110

being in elevation and the upper half showing a longitudinal section. Fig. 4 shows this radiator half in end view and half in transverse section along line 4—4 of Fig. 3.

- 5 In the radiator shown in Figs. 1 and 2 the tubes A are arranged uniformly in a circular layer, preferably single, and around the periphery of an ovoid having a geometrical axis X—X which is parallel or 10 practically parallel to the direction of flight, that is to say to the longitudinal axis of the airship. The tubes open at their front ends into an annular collector B and at the rear into a collector C. The collectors are 15 supported by a shaft D, placed along the geometrical axis X—X of the radiator, and which may be formed of a single tube of which the part comprised between the collectors is cut off from the ends by plugs E, 20 F. The ends of the tube are rotatably mounted in supports G, H, which may be arranged at any suitable point on the airship. The whole of the radiator which can be made to rotate about its axis for inspection, repair or removal of damaged tubes 25 is supported on the ends of the tube D, which ends are connected by means of removable joints d, d, to the circulating pipe I for the cooling water.
- 30 The front collector B is connected to the tubular shaft D by the tubes b. The collector B is preferably of streamline form as shown in Fig. 1, so as to reduce the resistance of the air. The rear collector C is 35 in communication with the rear of the tubular shaft D through openings c pierced in the said shaft. The tubes A are also of streamline form having their maximum diameter toward the interior a of the layer 40 formed by the bundle, while it contracts to a point toward the exterior a¹ as shown by the section at the left hand side of Fig. 2. In order to insure more rigidity to the radiator as a whole the tubes may, at an intermediate point of their length, be supported 45 in notches or recesses in the outer edge j of a metal ring J.
- The particular form given to the tubes while insuring an excellent circulation of 50 water at or about the part a of maximum diameter facilitates the flow of air around each of them and avoids the formation of a vacuum or partial vacuum due to this flow. The curvature of the tubes presents besides 55 the advantages already pointed out viz., that of facilitating flexions and dilations which notably reduce the chances of breakage at the soldered parts which is so frequent in tubular radiators with straight tubes.
- 60 In Figs. 3 and 4 the tubes A of the radiator are distributed in a single layer, or if necessary, in a plurality of layers, around the geometrical axis X—X and open, at their ends respectively at the front into an 65 annular collector B and at the rear into a

collector C. These collectors are supported by a shaft D formed by a tube of which the part comprised between the collectors is shut off from the ends by plugs E, F. Removable couplings d, d connect the whole of 70 the radiator to the water circulating pipe I.

The collectors B and C are each divided by partitions g, h, respectively into three units capable of being shut off by cocks. In case of damage to a tube it is possible by 75 closing the cocks B¹ and C¹ of the front and rear units into which the tubes open to isolate the said element or unit while the circulation continues in the other units of the radiator.

The front collector B is extended toward the interior forming a drum B² which advantageously cuts up the air entering by the outside of the tubular bundle.

The rear collector C is prolonged toward 80 the exterior forming a cone, which increases its capacity and permits at the same time of the formation of a directing surface for the flow of air at its outlet. In each of the units of the said rear collector is arranged 85 a tube C² open in front but closed at the rear, and extending over the major part of the length of the unit. This tube is split 90 longitudinally adjacent to axis opposite the water inlet in the unit, the corresponding cut 95 off cock C¹ being placed at the closed end of the tube which may unite with the continuous bottom C³ of the inlet chamber of the collector. The outlet pipe of the cocks C¹ opens in this case, into an outlet chamber 100 C⁴ which communicates by the openings c with the water outlet pipe. This pipe is capped with a cone of aluminium, C⁵ formed as a continuation of the rear collector and completing the streamline form of the whole. 105 The split tubes C² insure the circulation of the water in the rear collector. They prevent the direct passage of this water from the outlet of the tubes through the cut off cocks.

110 The radiator may be advantageously provided with a filling device such as shown in Figs. 1 and 2.

A circular chamber K of suitable form, 115 communicates by a pipe L, with the collector B. This chamber which may be closed by a spring actuated valve M placed in a removable cover N, forms a condenser for any steam which is separated from the circulating water. The chamber K also 120 forms a funnel and facilitates the filling of the collectors and radiator when the cover has been removed by merely removing the hook bolts O.

125 It is obvious that the radiator has been constructed to allow of rapid access to all its parts for the purpose of repairs. Each of the parts can be replaced or repaired without there being any need to partially or completely dismantle the apparatus. 130

As above stated, the rotation of the apparatus about the axis X—X in the supports G and H allows any tube to be brought within reach of the pilot.

5 The details of construction of the radiator above described may of course vary without departing from the nature of the invention.

I claim as my invention—

10 1. A radiator for motors of flying machines, and the like, comprising a plurality of tubes spaced apart and uniformly arranged around a common horizontal axis so as to form a continuous stream line, a forward and rear collector communicating with said tubes and each formed of an annular chamber, the said collectors being arranged in planes at right angles to the said axis, and a supply and exit pipe for the 20 circulating medium, respectively communicating with the forward and rear collector.

15 2. A radiator as specified in claim 1, in which the tubes are arranged in the periphery of an ovoid figure presenting its minimum cross-section to the rear and its maximum cross-section to the front.

25 3. A radiator, as specified in claim 1, in which the annular forward collector is of stream-line shape, radial tubes being provided for connecting it to the inlet pipe for the 30 circulating water.

35 4. A radiator, as specified in claim 1, in which the two collectors are connected and supported by a shaft formed by a tube, bearings for the ends of said tube being provided enabling the entire radiator to

be turned about its longitudinal axis thereby facilitating access to the various tubes.

5. A radiator, as specified in claim 1, in which the two collectors are each divided 40 into compartments, the forward collector extending toward the interior of the radiator forming a drum, thereby facilitating the flow of air as it enters, the rear collector being extended outwardly forming a cone 45 thereby increasing its capacity and controlling the flow of air as it passes out.

6. A radiator, as specified in claim 5, in which a longitudinally split tube is arranged in each compartment of the rear 50 collector forcing the cooling medium to circulate in said split tubes, a cut-off valve being also provided for each compartment.

7. A radiator for motors of flying machines and the like, comprising a forward 55 and rear collector arranged in planes at right angles to a horizontal axis parallel with the longitudinal axis of the flying machine, a pipe communicating with said two collectors, and a plurality of spaced tubes 60 between the said collectors arranged around said horizontal axis and having streamline form with their maximum diameter toward the interior of the radiator and contracted to a point toward the exterior 65 of the radiator.

In testimony whereof I affix my signature in presence of two witnesses.

ALEXANDRE LAMBLIN.
